Primary Examiner — Michael A. Pratt(74) *Attorney, Agent, or Firm* — Fox Rothschild LLP(57) **CLAIM**

The ornamental design for a trigger mechanism, as shown and described.

DESCRIPTION

FIG. 1 is a perspective view of a trigger mechanism according to the present disclosure.

FIG. 2 is a left side view of the trigger mechanism of FIG. 1.

FIG. 3 is a right side view of the trigger mechanism of FIG. 1.

FIG. 4 is a rear view of the trigger mechanism of FIG. 1.

FIG. 5 is a front view of the trigger mechanism of FIG. 1.

FIG. 6 is a top view of the trigger mechanism of FIG. 1.

FIG. 7 is a bottom view of the trigger mechanism of FIG. 1; and,

FIG. 8 is another right side view of the trigger mechanism of FIG. 1.

The broken lines in the Figures are for illustrative purposes only and form no part of the claimed design.

1 Claim, 6 Drawing Sheets(56)
